UNITED STATES PATENT OFFICE.

ALBERT GURNEY HOUGH, OF HIGH POINT, NORTH CAROLINA.

FOLDING DRAWER-DESK.

No. 829,156.

Specification of Letters Patent.

Patented Aug. 21, 1906.

Application filed December 8, 1905. Serial No. 290,973.

To all whom it may concern:

Be it known that I, ALBERT GURNEY HOUGH, a citizen of the United States, residing at High Point, in the county of Guilford 5 and State of North Carolina, have invented certain new and useful Improvements in Folding Drawer-Desks; and I do hereby declare the following to be a full, clear, and exact description of the invention, such as will 10 enable others skilled in the art to which it appertains to make and use the same, reference being had to the accompanying drawings, and to the letters of reference marked thereon, which form a part of this specification.

This invention relates to new and useful 15 improvements in folding drawer-desks for bureaus, &c.; and the object of the invention is to produce a simple and efficient device of this character which may be applied to a casing or cabinet, chiffonnier, or other article of 20 furniture in the place of an ordinary drawer and have the appearance of the latter when closed within the casing.

The invention consists, further, in a folding 25 drawer-desk so constructed that when it is withdrawn from the drawer-opening of a cabinet or casing and the desk opened means will be actuated whereby the desk may be held from being entirely withdrawn or pushed 30 back within the casing until the folding part of the drawer-desk is closed.

Another feature of my invention consists 35 in the hinging of a drawer-front to the folding drawer-desk and which front is turned down out of the way automatically as the desk is opened, and as the latter is closed the drawer-front will return to its normal position and give the external appearance of the usual drawers which may be positioned in 40 the cabinet.

My invention is illustrated in the accompanying drawings, in which—

Figure 1 is a front view of a cabinet or chiffonnier in which my improved folding drawer-desk is mounted. Fig. 2 is a perspective view showing the desk withdrawn and the folding part of the desk opened. Fig. 3 is an enlarged detailed view of the mechanism for locking the drawer-desk from being entirely withdrawn from the casing or from being returned within the casing after being partially withdrawn and the desk opened. Fig. 4 is a sectional view through the hinge connections of the folding drawer-desk. Fig. 5 is a sectional view on line 5 of Fig. 3.

Reference now being had to the details of

the drawings by letter, A designates a casing or cabinet of any suitable style having the usual drawers B therein, and C designates a drawer-front which is adapted to be similar 6c to the fronts of the other drawers and to give the appearance of one of the series, but being the front of my improved folding drawer-desk. Said front C is hinged at its bottom to the under section D of my improved folding 65 drawer-desk and also having pivotal link connections with the folding portion D' of the desk through the medium of the links E, which are pivoted at their inner ends to the blocks F upon the folding part D' and also to 70 the blocks C' upon the rear face of the front C. The two sections D and D' of my improved folding drawer-desk are connected together by hinges H, the leaf of each hinge being preferably bent at right angles, as at H', 75 and each fitted over an angled portion of the meeting ends of the two sections D and D', thus securely bracing the latter. To the ends of the folding section D' are fastened 80 the plates N, each of which has swivelly connected therewith a guide-strap M, in which a supporting-arm O slides, the inner end of which arm is connected to a pivot O', which is fastened to the side of the section D, as clearly shown in the detail view of the drawings. The upper edge of the section D of the folding drawer-desk is recessed or cut away 85 and is adapted to receive the folding part D' when the latter is closed, whereby when the two are folded together their opposite edges 90 will be in parallel planes.

Projecting from the face of the section D is a pin J, upon which the link I is pivotally mounted, and R designates a locking-arm of any suitable material which is pivotally 95 mounted at one end upon the pin L, mounted in the block L', and a spring P bears against said arm R and has a tendency to throw the same and also the link I away from the outer face of the section D. The free end of the 100 arm R has a projection R', forming a hook which is adapted to engage the inner edge of the post A' of the casing or chiffonnier to prevent the drawer-desk being entirely withdrawn from its casing when the folding part 105 of the desk is opened out. Said arm R also serves as a means to prevent the desk being pushed back within the casing by the angled end of said arm coming in contact with a strip R², secured to the inner face of the end 110 of the casing, it being understood that the means described is afforded to prevent the re-

turn of the drawer-desk to a position within the cabinet or casing or the entire withdrawal of the desk when the folding part of the desk is opened, it being required to first 5 close the folding part before it is possible to return the drawer-desk to its position within the casing or to allow for its entire removal from the casing. Said arm O is so positioned with relation to the link I that when 10 the folding part D' of the desk is closed over upon the recessed part D the inner face of the arm O bearing against the outer face of the link I will cause the latter to be thrown toward the face of the section D, and as the 15 link I is pivoted to the arm R the latter will also be thrown back under the tension of the spring P in contact with the outer face of the section D, which will throw the angled projection R' upon the arm R and said link I 20 clear of the strip R² on the casing, thus allowing the folding drawer-desk to be pushed back into the casing with the folding face C of the desk flush with the face of the casing to allow the drawer-desk to be entirely removed, 25 if desired, without being unfolded.

While I have described an apparatus as applied to one side of the drawer, it will be understood that each side of said drawer is equipped with similar apparatus.

30 From the foregoing it will be observed that by the provision of my improved folding drawer-desk the same may be applied to any of the places occupied by the usual drawers of a cabinet, chiffonnier, or other article of 35 furniture, and may have a straight front or oval or other form to correspond with the usual drawers and have the appearance of an ordinary drawer-front when closed within the casing and may be positioned within the casing 40 at such a location that the desk will be at a convenient height for a person while sitting or may be placed above, so that a person may use the desk while standing.

When the folding section of the desk is 45 opened out, it will be securely braced and held by means of said arm O, which is pivoted at its inner end to the section D and is fulcrumed over the upper edge of the outer end of the section D', as shown clearly in the 50 sectional view of the drawings. The folding part is also braced by a portion of the under surface thereof resting upon the block or projection to which the hinges are connected, which fasten the folding front to the section 55 D, thus affording a rigid writing-surface which will bear any reasonable weight which might come upon the same incident to its various uses.

What I claim is—

60 1. In combination with a drawer-desk adapted to be mounted in an ordinary bureau, casing or chiffonnier, &c., and having the external appearance of the other drawers, means for preventing the entire withdrawal 65 of the desk or its return within the casing

while the folding part of the desk is opened out, and a drawer-front carried by said desk and adapted to fold down as the desk is opened, as set forth.

2. In combination with a drawer-desk 70 adapted to be mounted in an ordinary bureau, casing or chiffonnier, &c., and having the external appearance of the other drawers, means for preventing the entire withdrawal of the desk or its return within the casing 75 while the folding part of the desk is opened out, and a drawer-front having hinge connections with the stationary and folding sections of the desk-drawer, as set forth.

3. In combination with a drawer-desk 80 adapted to be held in an ordinary drawer-opening of a casing or cabinet, means for preventing the desk from being entirely withdrawn or returned within the casing while the folding part of the desk is opened, a 85 drawer-front hinged to the stationary part of the desk, and a link pivotally connecting said drawer-front to the folding part of the desk, said front designed to turn down underneath the folding part of the desk as the 90 latter is opened, and to close over the hinged portions of the desk as the latter is closed, as set forth.

4. In combination with a drawer-desk 95 adapted to be held in an ordinary drawer-opening of a casing or cabinet, means for preventing the desk from being entirely withdrawn or returned within the casing while the folding part of the desk is opened, a 100 drawer-front hinged to the stationary part of the desk, links pivotally connecting said drawer-front to the folding part of the desk, and supporting-arms pivotally mounted upon the stationary part of the desk and 105 slidably connected with the folding part of the desk, said arms adapted to be fulcrumed over the hinged edge of the stationary part of the desk when the folding part thereof is 110 opened, as set forth.

5. In combination with a drawer-desk 110 adapted to be held in an ordinary drawer-opening of a casing or cabinet, means for preventing the desk from being entirely withdrawn or returned within the casing while the folding part of the desk is opened, a 115 drawer-front hinged to the stationary part of the desk, links pivotally connecting said drawer-front to the folding part of the desk, supporting-arms pivotally connected to the stationary part of the folding desk, and 120 swiveled members mounted upon the folding part of the desk and through which said arms are guided, the under edges of said arms adapted to be fulcrumed over the hinged edge of the stationary part of the desk when 125 the desk is opened out, as set forth.

6. In combination with a drawer-desk 130 adapted to be held in an ordinary drawer-opening of a casing or cabinet, means for preventing the desk from being entirely with-

drawn or returned within the casing while the folding part of the desk is opened, a drawer-front hinged to the stationary part of the desk, links pivotally connecting said 5 drawer-front to the folding part of the desk, supporting-arms pivotally connected to the stationary part of the folding desk, plates fixed to the folding part of the desk, and a swiveled member mounted upon each of said 10 plates and through which one of said arms has a play as the folding part of the desk is opened and closed, the under edge of each arm designed to be fulcrumed over the hinged edge of the stationary part of the desk 15 to support the folding section of the latter when opened, as set forth.

7. In combination with a drawer - desk made up of two sections which are hinged together and adapted to fold one upon the 20 other and when folded to occupy the space of an ordinary drawer of a casing or cabinet, a folding drawer-front having pivotal connections with the desk, arms pivoted to the stationary part of the desk and having a sliding 25 pivotal connection with the folding part thereof, a spring-pressed desk-retaining member pivotally mounted upon the stationary part of the desk, and a link pivotally connecting said retaining member and stationary 30 part of said desk, said link being positioned in the path of one of said arms, which connect the two sections of the desk, and so arranged that when the folding section of the desk is turned back, said retaining member 35 and link are thrown toward the side of the desk to allow the latter to be pushed within the casing, as set forth.

8. In combination with a drawer - desk made up of two sections which are hinged together and adapted to fold one upon the 40

other, their opposite faces when folded being in parallel planes designed to fit the drawer-opening of a casing or cabinet, a folding drawer-front having hinge connections with the stationary section of the desk, arms pivotally connected to the stationary part of the desk and sliding pivotal connections with the folding part of the desk, desk-retaining members, each pivoted to a side of the stationary part of the desk and each having an angled end, a spring serving to normally throw each of said members away from the desk, and links each pivotally connecting the stationary part of the desk with one of said desk-retaining members, the inner faces of 55 said arms connecting the two sections of the desk adapted, as the folding part of the desk is closed, to bear against the outer faces of said members and cause the latter to be thrown toward the end of the desk, as set forth.

9. In combination with a drawer - desk comprising a stationary and a folding section, a hinge, the wings of which are angled and fastened over shoudered portions of said 65 desk-sections, links pivotally connecting the stationary and folding parts of the desk, a drawer-front hinged at its lower edge to the stationary part of the desk and having pivotal link connections with the folding part of 70 the desk, and pivotal arms mounted upon the stationary part of the desk and having sliding connections with the folding part of the desk, as set forth.

In testimony whereof I hereunto affix my 75 signature in the presence of two witnesses.

ALBERT GURNEY HOUGH.
